UNITED STATES PATENT OFFICE.

JOSEPH M. SCHREMS, OF SAGINAW, MICHIGAN.

VENT-CAP FOR SOIL-PIPES.

1,256,045.

Specification of Letters Patent. Patented Feb. 12, 1918.

Application filed September 22, 1917. Serial No. 192,685.

To all whom it may concern:

Be it known that I, JOSEPH M. SCHREMS, a citizen of the United States, residing at Saginaw, in the county of Saginaw and State of Michigan, have invented certain new and useful Improvements in Vent-Caps for Soil-Pipes; and I do hereby declare the following to be a full, clear, and exact description of the invention, such as will enable others skilled in the art to which it appertains to make and use the same.

This invention relates to caps for soil pipes and the like. The object of the improvement is to provide a strong and durable soil pipe cap of light construction that can be easily and quickly attached to a soil pipe and clamped thereto without the aid of special tools other than a screw driver or its equivalent.

My invention is illustrated in the accompanying drawings, in which Figure 1 is a top plan view of the cap.

Fig. 2 is a part sectional side elevation of the cap applied to a soil pipe.

Fig. 3 is a side view of the cap with the clamping or locking device expanded and showing in dotted lines the same device in its retracted position. The clamping bolt is omitted from this view in solid lines for clearness in illustrating.

As is clearly shown in the drawings, the device comprises a metal cap 1, which is preferably stamped from sheet metal and is preferably in the form of an inverted bowl. The cap is provided with a central aperture 2, and a plurality of depressed pockets 3 formed by the same stamping operation by which the cap 1 is formed. Each pocket has a rear wall 4 and a horizontal bottom 5. The pockets are preferably arranged in pairs diametrically opposite each other, as shown in Fig. 1.

A clamping frame is secured to the horizontal bottoms 5 of the two opposite pockets, as shown in Figs. 2 and 3. This frame comprises a pair of downwardly extending arms 6, 6 secured at their upper ends to the bottoms 5 and adapted to project down into the pipe 7.

The lower ends of the arms 6, 6 are connected by a downwardly bowed flexible cross brace 8 preferably made of a flat steel bar or its equivalent. A similar upwardly bowed cross brace 9 connects the arms 6, 6 above the brace 8.

An internally threaded boss or nut 10 is carried by the flexible cross brace 8 and receives the threaded end of a bolt 11. The upper end of the bolt passes loosely through an opening in the upwardly bowed brace 9 and is provided with a lower collar or washer 12, which may be held in place by a cotter pin 13, and is also provided with an upper washer 14 of large diameter.

When the bolt 11 is tightened by means of a screw driver the flexible bowed cross braces 8 and 9 are forced toward each other and partly straightened, thus forcing the lower parts of the arms 6, 6 outward to yieldingly clamp against the inner walls of the pipe 7, as indicated in Fig. 3.

The device is applied to the pipe by first inserting the arms 6, 6 into the pipe and pushing the cap down until the bottoms 5 of the pockets 3 rest on the end of the pipe. A screw driver or equivalent tool is then inserted through the central aperture 2 and the bolt 11 is tightened.

To remove the cap 6 it is only necessary to unscrew the bolt 11 sufficiently to release the clamping frame, after which the device may be lifted from the pipe.

To prevent sticks, etc., from being dropped into the pipe 7, I prefer to make the upper washer 14 of sufficiently large diameter to catch any such articles that might be dropped through the opening 2, which otherwise might obstruct the soil pipe.

Having thus described my invention, what I claim and desire to secure by Letters Patent is:

In a soil pipe, the combination of a pressed metal cap having diametrically opposite pockets formed therein, a pair of downwardly extending flexible arms secured at their upper ends to the bottoms of said pockets, a downwardly bowed flexible cross brace secured to the lower ends of said

arms, an upwardly bowed flexible cross brace secured to said arms intermediate their length; a threaded boss carried by said lower cross brace, a threaded bolt passing loosely through the upper cross brace and threaded into said boss, an upper and a lower washer on said bolt, said upper washer of large diameter, said cap formed with a

central aperture located above the head of said bolt, for the purposes set forth. 10

In testimony whereof, I affix my signature in presence of two witnesses.

JOSEPH M. SCHREMS.

Witnesses:

NELLIE M. ANGUS,
ROY WALLIS.
